BELT LACING APPARATUS

Harry James Camp, Enfield, and Charles Watson, Chingford, London, England

Application April 25, 1939, Serial No. 270,038
In Great Britain June 15, 1938

6 Claims. (Cl. 140—93)

This invention relates to belt lacing apparatus and has for its object the provision of an improved apparatus for effecting the flattening of wire helices which are threaded into belt ends to constitute parts of a belt connection.

Belt connections are known wherein a lacing strip or a multiplicity of staples is secured to the belt end by forcing the hooked or otherwise appropriately shaped ends of the elements into the material forming the belt by means of a clamping operation in order to obtain loops, and in relation to this form of belt connection it has been proposed to employ a clamping apparatus incorporating a removable pin which, during the clamping operation has constituted a former about which the lacing strip or each staple has been turned or folded, in some cases in conjunction with stop means on one or the other of the clamping jaws of the apparatus for the purpose of holding up the strip or staple against the former during the turning or folding operation.

Regarding the type of connection with which the present invention is concerned it is already known to use spaced punches to punch the ends of a belt with spaced and inclined apertures and to thread in each end a helix of wire. Subsequently the two helices are flattened, after which they are caused to mesh and between the overlapping parts is threaded a cord or the like of raw-hide to form the connecting member.

Machines are known for punching the spaced and inclined apertures in the belt ends and also in the same machines, as a subsequent operation, for flattening the helical wires threaded into the said punchings. Additionally in such machines it has also been proposed to incorporate means whereby the wire helices may be constructed from ordinary wire.

With this latter type of belt lacing apparatus the flattening operation on the helices of wire, before their interconnection, has resulted in a certain shaping of the interconnecting part which has disadvantages. In other words, the shaping of the end of the flattened helices which, during the driving of the belt engages the interconnecting cord of rawhide or otherwise, has been that which the helical wire would take purely by the flattening action.

However, with apparatus according to the present invention the interior shape of this portion of the flattened helix can be made to agree exactly with the exterior surface of the interconnecting cord.

Thus, according to the present invention an apparatus for flattening a wire helix threaded into a belt end to constitute part of a belt connection, comprises clamping jaws, spaced pins on one of said jaws for locating the turns of the helix projecting from the end of the belt when said end is placed within the jaws, and a former for location in the turns of the helix, the said spaced pins forming stop means for holding the former against the interior of said turns, during the relative movement of the clamping jaws that serves to flatten the turns of the helix, so that the interior shape of the outer end of the flattened helix will correspond to the adjacent surface of the former. By choosing a former having a surface shaped to correspond with the exterior surface of the connecting cord, it will be obvious that the interior shape of the outer end of the flattened helix will agree exactly with said exterior surface of the connecting cord.

In most cases the interconnecting rawhide cord or the like is of circular section and thus the former is given a substantially semi-circular cross sectional shape. Thus, when the two adjacent flattened helices are in position the connecting member can readily be included between them and the same circular engaging part of each portion of both flattened helices contacts with the said interconnecting member throughout its extent.

In order that the invention may be better understood, it will now be described with reference to the accompanying drawing in which:

Fig. 1 shows an elevation from one side of a belt lacing apparatus of the type to which the invention relates and to which the invention is applied.

Fig. 2 is an end elevation of Fig. 1.

Fig. 3 is a similar view to Fig. 1 but taken from the other side of the apparatus.

Fig. 4 is an enlarged sectional side elevation illustrating a preferred form of the invention.

Fig. 5 is a somewhat diagrammatic plan view in section of certain parts shown in Fig. 4.

Fig. 6 is a similar view to Fig. 4 but showing the parts thereof in another position.

Fig. 7 is a side elevation of a joint between adjacent ends of a belt with the ends of the helices formed by apparatus in accordance with the invention.

Fig. 8 is a view, somewhat similar to Fig. 6, showing a modification.

Fig. 9 shows a similar view to Fig. 7, but of the joint between the helices formed in appa-

ratus already known, to illustrate the structural defects of the joint attained by such old machines.

The apparatus shown in Figs. 1, 2 and 3 is of a generally known character except for the part 5 which is constructed according to the invention and comprises on one side a mouth 10 to receive the belt end to have the angularly inclined spaced perforations made therein by punching pins 11 carried by a backing plate 12 subject to the 10 action of a cam 13 controlled by a lever handle 14 to cause movement on a central post or pillar 15.

By this means upon the insertion of the belt end therein it is given the desired row of angularly inclined punchings.

On the other side of the machine, also as is known, are arranged similarly spaced pins 16 between which the turns of the helix which has been threaded through the belt end are placed 20 prior to their flattening.

If desired the machine also can have combined therewith, in a known manner, a threaded bore 17 to receive a cranked spindle 18 into which one end of a wire is secured, so that by turning 25 on the said cranked spindle the helix may be formed thereon. The parts are of such size that the turns of the helix are spaced according to the pitch of the pins 11 and 16.

In such machines as previously constructed, 30 when the helix in the end of the belt has been inserted between the pins 16 into the mouth 19 in which these pins are arranged, it has been flattened without any guidance, resulting in a structure such as shown in Fig. 9 wherein there are 35 flats such as 20 formed on each side of the flattened end of the helix and a pointed part 21. From a study of Fig. 9 it will be seen that the result is the interconnecting member (of rawhide or the like) 22 only has certain what may be 40 called points or zones of contact.

It is the purpose of the present invention to obviate this defect and in accordance with the invention the mouth 19 has at the rear thereof a downwardly projecting plate or flange 23 the 45 surface 24 of which is spaced from the nearest points of the pins 16 by a distance representing the gauge of the wire in the helix and the radius of the interconnecting member 22.

As shown in Figs. 4 and 5, the helix 25 in the 50 belt end 26 is located between the pins 16 and between the pins 16 and the portion of the helix coming adjacent the plate or flange 23 is located a former 27 of semi-cylindrical shape, this former having the diameter of the interconnecting member 22. It will thus be apparent that when the backing plate 12 descends to cause the helix to be flattened between the fixed lower jaw and the movable upper jaw and into the position 55 shown in Fig. 6, the helix 25 must wrap itself around the former 27 as shown in Fig. 6 to give a semi-circular formation 28 to the end of the turns of the helix.

Thus, when removed from the apparatus, two such flattened helices can be connected as shown 60 in Fig. 7 so that the interconnecting member 22 is contacted with by the semi-circular parts of the helices, obviously to give an improved result.

To facilitate the action and to prevent any possibility of the adjacent portions of the wire of 65 the helix 25 being damaged, scored or otherwise weakened, the lower portion of the surface 24 may be rounded at 29 and if desired slightly bevelled at 30.

In some cases in order to utilise a standard

diameter interconnecting member 22 for belts of a thickness varying from a minimum to a maximum, the portion of the jaw 31 (Fig. 8) carrying the downwardly projecting plate or flange 23 coming at the upper inner corner may be recessed, for example this recess may have a rounded formation such as shown at 32. Similarly, if desired the fixed jaw 33 may have a slight rounding such as at 34.

Although the invention has been more particularly described with reference to a combined machine for the formation of the helix and for carrying out the punching operation, yet it will be obvious that it is not limited thereto. For example, it may merely comprise the clamping 10 means for flattening the helix and shaping the projecting ends of the turns thereof. Again, although the movable jaw of the apparatus has been described as carrying the parts for maintaining the former in position and for constituting the stop means for the helix, yet as will be understood one or both of these parts may be on the fixed jaw. Further, in some forms of apparatus both jaws may be movable, for example in a hand-operated tool somewhat resembling a 15 pair of pliers.

Further, although the apparatus described performs the flattening of the whole axial length of the helix at the same time, yet in some forms the apparatus may be such that it only does a part 20 of the axial length, for example even one turn of the helix. In this last-mentioned case, however, means preferably would be included in the structure for maintaining the requisite spacing between the turns when flattened.

The invention is not limited to the precise forms or details of construction described, as these may be varied to suit particular cases.

What we claim and desire to secure by Letters Patent of the United States of America is:

1. Apparatus for flattening a wire helix threaded into a belt end to constitute part of a belt connection, comprising clamping jaws, spaced pins on one of said jaws for locating the turns of the helix projecting from the end of the belt 45 when said end is placed within the jaws and a former for location in the turns of the helix, the said spaced pins forming stop means for holding the former against the interior of said turns, during the relative movement of the clamping jaws 50 that serves to flatten the turns of the helix, for the purpose set forth.

2. Apparatus as claimed in claim 1, wherein one of the clamping jaws is formed or provided with a portion adapted to bear against the exterior of the helix to constitute a stop for holding up the turns of the helix against the former during the clamping operation.

3. Apparatus as claimed in claim 1, wherein the clamping jaws are shaped to assist in the 60 shaping of the projecting turns of the helix for the purposes set forth.

4. Apparatus as claimed in claim 1, including spaced punches for angularly perforating the belt ends, substantially as set forth.

5. Apparatus as claimed in claim 1, including means for winding the wire helices, substantially as set forth.

6. Apparatus as claimed in claim 1, wherein the former is such as to obtain substantially 70 semi-circular bends at the outermost part of the projecting turns of the helix.
